his Attorney

UNITED STATES PATENT OFFICE.

ARTHUR FRANCIS ROWE, OF LEATHERHEAD, ENGLAND.

CASE FOR CIGARETTES AND OTHER ARTICLES.

Application filed November 17, 1924. Serial No. 750,405.

To all whom it may concern:

Be it known that I, ARTHUR FRANCIS ROWE, a subject of the King of Great Britain, residing at 16 The Crescent, Leatherhead, 5 Surrey, England, have invented Improvements in and Relating to Cases for Cigarettes and Other Articles, of which the following is a specification.

This invention relates to improvements in cases for cigarettes and other articles but more particularly to cigarette, cigar and like hinged foldable cases and has for its primary object the substitution of a spring controlled device for holding the cigarettes or cigars 10 within such cases in place of the usual elastic tape or band. In cases of the latter type, particularly cigarette cases, it is usual to employ an elastic tape stretched from one side of the case to the other in order to 15 position the cigarettes in place, now these elastic tapes not only perish and quickly lose their resiliency, especially in warm climates, and are difficult to renew, but they also make it difficult to extract a cigarette 20 without damaging it. Moreover in curved or shaped cases in which provision is made for a double row of cigarettes, the cigarettes on the one side are tightly pressed by the retaining band, whilst those on the other 25 side are loosely held due to the convex and concave surfaces respectively on which they rest. Now the present invention not only overcomes these drawbacks but also allows the case to be more readily filled and 30 emptied.

The present invention as applied to a single row, or to each side of a double row, cigarette case comprises essentially a spring supported and controlled clip consisting of 35 a retaining bar and side pieces so shaped at both its ends that the retaining bar normally lies in contact with the cigarettes and retains them in position and is capable of being turned back clear of them or to allow 40 of being slightly raised by one cigarette when lifted for removal without in any way injuring it.

This invention will be now more particularly described making reference to the accompanying drawing in which:—

Fig. 1 is a view in front elevation of a double row cigarette case—in an open position—embodying the present invention, and

Fig. 2 is a perspective view of a similar cigarette case showing the functioning of the retaining clips.

Throughout both views similar parts are marked with like letters of reference.

A spring supported and controlled clip constructed according to the present invention consists of a transversely arranged retaining bar *a* of relatively thin metal of a length approximating the width of the case *x* and having side pieces *b* bent downwardly at right angles to the bar *a* and parallel with the sides of the case *x*. Within and on each side—parallel therewith—of the case *x* is carried the springs *c* supporting and controlling the bar *a*.

Each spring *c* consists of a length of 70 spring wire held at one end thereof to the side of the case by being inserted in and soldered to a looped metal projection or socket *d* formed on or attached to the lip or upper edge of the side of the case, the other 75 end of the spring wire is bent at right angles to engage a hole *e* near the end of the side piece *b* and terminates in a thickened head or if preferred this end of the spring may be bent into a hook to prevent its accidental 80 withdrawal from the hole *e*.

The downward pressure of the springs *c* causes the extremities of the side pieces *b* to take a bearing on or to fulcrum on the inner surface of the case on raising the retaining bar, see more particularly the left hand side of Fig. 2. These fulcruming extremities of the side pieces *b* are rounded off at *f* to prevent their cutting grooves or ruts in the inner surface of the case *x* and 85 such fulcruming extremities coincide with the ends of cigarettes when lying in a normal position with the case, so that as a cigarette is raised for withdrawal (see the right hand side of Fig. 2), its end follows 90 the same path as that of the fulcruming extremities of the side pieces *b*. The free ends of the side pieces *b* are further so shaped or bevelled off that when the retaining bar *a* is raised and passes a vertical position, the 100 springs *c* cause it to come to a position of rest clear of the contents of the case, as shown on the left hand side of Fig. 2 so as to enable the case to be readily filled with 105 cigarettes.

The springs *c* instead of being made from springy wire as shown, may be of the blade type.

The inner surface of the retaining bar *a* may in some cases be lined with a strip of 110 velvet, india rubber or the like or may be coated with a suitable material to enable it

better frictionally to engage or grip the cigarettes when lying normally in the case.

When the device is applied to a curved or shaped case, see Fig. 2, the retaining bars *a* are curved to correspond to the curvature of the case, and when the device is applied to a double row case, as illustrated, the retaining bar *a*, side pieces *b* and controlling springs *c* are placed in one side of the case in an inverted position to that occupied by the bar, side pieces and springs in the other side of the case and so that the bars *a* do not coincide when the case is closed.

Although this invention has been specifically described with reference to cigarette cases, it will be understood that with necessary modifications it is equally applicable to cigar cases or other cases adapted to contain a number of regularly shaped articles placed side by side such as variously coloured pencils, crayons or chalks.

I declare that what I claim and desire to secure by Letters Patent is:—

1. In a case for cigarettes and other articles, a spring supported and controlled clip

30 consisting of a transverse retaining bar of relatively thin metal, side pieces bent downwardly at right angles to the bar and parallel with the sides of the case and a pair of springs one for each side piece and each consisting of a blade spring held at one end to the side of the case, the other end engaging the free end of one of the side pieces of the retaining bar, as set forth.

35 2. In a case for cigarettes and other articles, a spring supported and controlled clip consisting of a transverse retaining bar of relatively thin metal, side pieces bent downwardly at right angles to the bar and parallel with the sides of the case and having their free ends rounded and bevelled off to fulcrum on the inner surface of the case on raising the bar, and a pair of springs one for each side piece and each consisting of a 40 length of spring wire rigidly held at one end to the side of the case, the other end being bent at right angles to engage a hole near the free end of one of the side pieces of the retaining bar, as set forth.

45 ARTHUR FRANCIS ROWE.
